UNITED STATES PATENT OFFICE.

JAMES ANDERSON, OF PARIS, FRANCE.

DEVICE FOR TRANSFORMING ICE INTO SNOW.

Application filed October 11, 1921. Serial No. 507,099.

To all whom it may concern:

Be it known that I, JAMES ANDERSON, a subject of the King of England, and resident of Paris, France, (post-office address 5 114 Avenue des Batignolles), have invented a new and useful device for Transforming Ice into Snow, which improvements are fully set forth in the following specification.

The present invention relates to a device 10 or apparatus for making snow by treating block or lump ice.

To enable the invention to be more clearly understood reference will be made to the appended drawings wherein:

15 Figure 1, is a general elevation of the apparatus,

Figure 2 is an enlarged elevation showing the ice-plane,

Figure 3, shows the cutter or cutting-tool 20 of the plane,

Figure 4, is a section of the ice slide.

As will be apparent from the following description, my invention is essentially characterized by the employment:

25 (a) of an ice-plane provided with two adjustable blades set in opposite directions;

(b) of an automatic device which permits the slide supporting the ice block to be given a progressive incline so as to keep 30 the said block constantly against the plane during operation of the machine.

The plane proper (Figure 2), driven by any known means (crank, motor etc.), is mounted on a support S secured to one end 35 of a frame B of any shape. This plane is constituted by an extended rectangular frame 1 made of wood or of any other material and comprising a central core or body 2 in which a hole 3 is provided to serve 40 as a housing for a driving shaft 4 connected with the motion-transmitting members.

On either part of this body 2 are slots or 45 ports 5 the inversely set parts of which (Fig. 2) carry blades 5' which are adjusted and held by means of any suitable device (nut, winged screw, etc.).

In order to start operation on the ice-block, a cutting tool 6 (Figure 3) shaped somewhat like the end or nose of a spiral 50 drill bit is screwed on the end of shaft 4. This cutter 6 furthermore increases adherence of the ice-lump to the plane.

A coil spring 7 or any other similar device suitably positioned around shaft 4 55 damps such shocks as may occur when the ice-block is being put on its slide-support

8 and, on the other hand, imparts great resiliency to the whole device.

In order to enable this damping or cushioning action to be obtained, the shaft 4 is 60 mounted to move endwise in its bearing on the support S; the aforesaid spring 7 tending to move the shaft in a direction away from said support and bearing (toward the left in Fig. 1). Hence when a block of ice 65 is deposited upon the inclined supporting trough 8, it will slide down the trough and strike against the cutter 6 on the shaft 4, which latter will thereby be moved toward the right, against the action of spring 7 70 which will take up and absorb the shock incidental to the blow.

As has already been explained, another characteristic of my invention resides in the fact that a member is provided which permits slide 8 to be given such an incline as will keep the block constantly and firmly 75 against the plane blades during operation.

In the embodiment shown by the drawing, this device is constituted by a simple rod 80 9, secured at C in a suitable housing where it is adapted to slide vertically, its upper end bearing on the rear part of support 8, which is adapted to swing or rock about a horizontal pivot D.

Around the said rod is wound a coil spring 11, the power of which is calculated to stand a predetermined weight of ice. As the ice block decreases under the action of the plane that transforms it into snow, the 90 spring expands and lifts the slide, thus imparting to the latter a progressively-increasing inclination.

This spring device is shown here only as an example but can obviously be of any 95 other shape or kind.

In the case when lump ice is to be treated slide 8 has only to be replaced by a gullet or hopper, combined or not with an ice-compressing device that will press it forcibly 100 against the plane blades.

It should be clearly understood that the means to drive the plane may be of any sort, type or kind, and that I reserve the right to modify according to cases or requirements the details of construction of the apparatus without departing from the principle of my invention.

Having now particularly described and ascertained the nature of my said invention 110 and the manner in which the same is to be performed, what I claim is:

1. An ice-shaving apparatus, comprising an inclined ice-supporting trough; an ice-shaving device at the foot thereof; and means acting to automatically adjust the 5 inclination of the trough in accordance with the weight of a block of ice on the trough.
2. An ice-shaving apparatus, comprising an inclined ice-supporting trough; an ice-shaving device at the foot thereof; and supporting means for the trough acting to automatically raise said trough as the block of ice thereon is gradually consumed by the shaving device.
3. An ice-shaving apparatus, comprising 15 a frame; an inclined ice-supporting trough pivoted thereto at its lower end; an ice-shaving device mounted on said frame in position to act upon the front face of a block of ice on the trough; and a spring device carried by said frame for supporting the upper end of the trough, said spring device acting to gradually raise said trough end as the block of ice is consumed by the ice-shaving device.
4. An ice-shaving apparatus, comprising 25 a frame, an inclined ice-supporting trough pivoted thereto at its lower end; an ice-shaving device mounted on said frame in position to act upon the front face of a block of ice on the trough; a vertical supporting member slidably mounted in said frame and engaging the upper end of said
- trough; and a spring operative on said member to gradually elevate the same and thereby raise the trough as the block of ice is 35 consumed by the shaving device.
5. In an ice-shaving apparatus, the combination of an ice-support, and an ice-shaving device located in position to act on the front face of a block of ice on said support; said device comprising a cutter shaft, driving means therefor, a cutter on said shaft, and a spring on said shaft to absorb shocks arising consequent upon the loading of the ice upon the ice-support.
6. In an ice-shaving apparatus, the combination of an ice-support, and an ice-shaving device located in position to act on the front face of a block of ice on said support; said device comprising an ice-plane provided 40 with a pair of oppositely-inclined blades, a driving shaft whereon said plane is mounted, means for rotating said shaft, and a spring on said shaft to absorb shocks arising consequent upon the loading of the ice 45 upon the ice-support.

In testimony whereof I have signed this specification in the presence of two subscribing witnesses.

JAMES ANDERSON.
